RIVET-FINISHING TOOL.

Application filed March 24, 1925, Serial No. 17,898. Renewed August 25, 1927.

This invention relates to a tool designed to be employed in combination with a pneumatic rivet calking machine for finishing or calking the heads of rivets after their formation.

In heading rivets of boilers, sheet metal tanks, and other metal structures in which parts are riveted to each other, the rivet heads do not always tightly engage the surface of the metal plate in which they are mounted, thereby causing leaky joints. Moreover frequently the riveters by an unequal application of power of the riveting machine form circular heads that are not concentric with the cylindrical shanks, and as a result a small portion of the holes in the metal sheet are uncovered. It has been the custom in view of the above to employ a hand tool to go over the finished rivet heads to calk or tighten the same, and frequently this fails to accomplish the desired tightening.

By means of the tool herein illustrated and described, rivet heads may be effectually tightened to their plates after their formation by the usual riveting machines, and defective rivet heads that do not fully cover the rivet holes can be straightened to form a tight joint without the necessity of replacing the defective rivet. Further by means of this tool an operator may start adjacent the apex of a conical rivet head and bring the stock down to the metal sheet and towards the shank of the rivet to tighten its circumferential edge in relation to the plate surface. Moreover the tool may be effectively employed in calking rivet heads mounted in flanges with less difficulty than in hand tightening operations.

Broadly the invention resides in a simple manually operated tool consisting of a frame provided with an adjustable means for holding the tool in operative relation to a rivet head, a pair of impact members oppositely disposed within the frame and adapted to deliver a succession of rapid blows to the rivet heads at diametrically opposite points, whereby to effectively and uniformly tighten the heads to the plates in which they are secured, the shank portion of the frame being provided with a reciprocating plunger adapted to be operated by the hammer member of a pneumatic rivet calking machine for actuating the impact members.

The specific features of the invention will

be readily understood from the following specification and the accompanying drawings, in which:

Fig. 1 is a side elevation of the rivet finishing tool applied in operative relation to a rivet head, the tool being shown in connection with a rivet calking machine.

Fig. 2 is a similar view with a part of the casing frame removed, and partly in section.

Fig. 3 is a partial side elevation of the tool, with a part of the frame removed therefrom, showing the method of forming the tool centering depression in a rivet head.

Fig. 4 is a transverse section of the tool taken on line 4—4 of Fig. 1.

Fig. 5 is a transverse section taken on line 5—5 of Fig. 1, illustrating the mechanism in operative relation for forming the centering punch in the rivet head.

Fig. 6 is a view similar to the above showing the centering punch mechanism in an inoperative position.

Fig. 7 is a perspective view of the outer portion of one of the rivet impacting members.

In the drawings, 10 designates the frame of the tool, preferably consisting of a pair of complementary cast metal members 11, 12, each provided adjacent their side edges with curved grooves 13, 14, the grooves in each member registering when the members are secured together, and are substantially square in cross section. The shank 15 of each member is semi-cylindrical in form and provided with a longitudinally extending bearing cavity 16, semi-circular in cross section. Each member is also provided with a centrally disposed longitudinally extending bearing 16', and a transversely disposed slot 17 extending across the bearing, the slots of each member registering when the same are bolted or otherwise secured together.

Mounted in the curved grooves of members 11, 12, are a pair of curved impact members 18, 19, their outer ends 20 being concaved (see Fig. 7.) in order that they may closely engage the convexed surfaces of the rivets when applied thereto, their inner ends being squared in order that the blow delivered by the tool hammer thereagainst will be uniform.

Disposed within the bearing cavity of the shank of the tool is a cylindrical shaft 21,

provided on the outer end thereof with a flat hammer head 22, the side edges 23 being angular and normally engaging the squared ends of the impact members 18, 19. As the width of head 22 is greater than the diameter of the hammer shaft, the walls of the shank adjacent the inner end are cut away as at 24 to provide for its movement on a reciprocation. Surrounding that portion of the shaft 21 is a coiled spring 25 bearing against the end of the shank and a collar 26 secured to the shaft.

Disposed within the centrally disposed bearing cavities 16 formed in the oppositely disposed faces of members 11, 12, is a rivet engaging centering shaft 27, threaded on its inner end for the reception of a circular adjusting nut 28, that is disposed in the transverse slots 17 of the frame members. The threaded end of shaft 27 is provided with a transversely disposed pin 29, its ends extending into longitudinally extending guide slots 30 that extend inwardly from the adjusting nut slots 17, thereby permitting of a reciprocation of said shaft on a rotation of the adjusting nut.

In order that the shaft 27 may be maintained in an adjusted position during the operation of the rivet finishing tool, a spring operated latching mechanism is provided, preferably consisting of a dog 30' mounted in a transversely extending recess 31 formed in the outer face of frame member 11, a coiled spring 32 normally forcing the serrated end of the dog 30' into engagement with the serrated periphery of the adjusting nut, see Fig. 4. The outer end of shaft 27 is provided with a conical recess 33 adapted to engage the apex of the conical rivet head when applied thereto, holding the tool firmly in pivotal engagement with the rivet head during the operation of the tool.

In the case of semi-spherical headed rivets as shown in Fig. 3, a centering shaft 35 having a conical point is employed, that engages a recess 36 formed in the head of the semi-spherical rivet.

The recess 36 in the semi-spherical rivet heads is preferably formed by means of the pointed centering shaft 35, a movable abutment mechanism being employed. This mechanism preferably consists of a shaft 37, provided with a head 38, and a rectangular abutment 39 formed on the lower end thereof, a flat transversely disposed spring 40 having its slotted ends secured to the upper surface of frame member 12, engaging the shaft 37 and holding the abutment 39 in an operative or inoperative position as clearly shown in Figs. 5 and 6 of the drawings. In operation the abutment member is pushed downwardly through an aperture 41 formed in frame member 12, until the head 38 is disposed between the inner end of the shaft 35, and the pointed head of the hammer 23,

see Figs. 3 and 5. In this position a blow imparted by the hammer will force the pointed end of the shaft 35 into the rivet head to form the recess 36, after the formation of the recess the abutment is withdrawn into the position shown in Fig. 6, and the tool can then be used in finishing or calking the rivet heads. It will be understood that when the abutment member 39 is in operative position to form the centering recess 36 in the rivet head, the hammer member 22 cannot contact with the ends of the impact members 18, 19, to operate the same.

The operation of the rivet finishing tool will be readily understood from the following. The outer end of shaft 21 is inserted in the cylindrical bore 45, formed in the outer end of a pneumatic rivet calking machine 46, the machine hammer 47 contacting therewith. Centering shaft 27 is then placed against the conical end of the rivet, see Fig. 1, and the pneumatic rivet calking machine is then set in operation, the blows of its hammer, 47 being imparted to the impact members through the medium of the shaft 21 carrying the hammer head 23, and as said members are oppositely disposed the blows delivered to the rivet head will be absolutely uniform.

It will be understood that in a finishing operation the impact members 18, 19, are adjusted so that they engage the conical surface of the rivet head intermediate its base and apex, see Fig. 1, the shaft 27 being retracted and the tool rotated during the operation until the impact members finally engage the circular edge of the rivet head to form the annular bead 48, see Fig. 2, this adjustment of the impact members forcing the stock of the head downwardly towards its base and forming a leak proof joint. Shank 15 of the tool is provided with a cylindrical sleeve 49, knurled on its outer surface to furnish a hand hold for the machine operator.

From the above it will be apparent that I have produced a comparatively simple tool that will efficiently perform the finishing operations on rivet heads, effectually sealing them in leak proof engagement with their metal plates, and in the case of rivet heads that are not formed concentric with their bodies, or which are tilted slightly, as the rivet head shown in Fig. 1, the tool will readily correct such imperfections. Further the finishing tool will complete the final finishing operation on rivet heads in less time than required in hand finishing operations.

What I claim is:

1. A rivet finishing tool comprising a frame provided with grooved guideways, a pair of reciprocable impact members mounted in said guideways adapted to contact with the surface of a rivet head, and means to actuate said members.

2. A rivet finishing tool comprising a frame provided with grooved guideways, a pair of oppositely disposed reciprocable impact members mounted in said guideways 5 adapted to contact with the surface of a rivet head, and means to actuate said members.
3. A rivet head finishing tool comprising a frame provided with a pair of oppositely disposed grooved guideways, a pair of reciprocable impact members mounted in said guideways, their outer ends adapted to contact with the surface of a rivet head, and means to deliver blows intermittently 10 against the inner ends of said impact members.
4. A rivet head finishing tool comprising a frame provided with a pair of oppositely disposed grooved guideways, a pair of reciprocable impact members mounted in the guideways of said frame, their outer ends adapted to engage a rivet head, a centering shaft adjustably mounted in said frame for pivotally engaging a rivet head, a hammer member disposed in said frame for intermittently delivering blows to the impact mem- 15
- bers on an operation of the tool, and means to reciprocate the hammer member.
5. A rivet finishing tool comprising a frame provided with a pair of oppositely disposed curved guideways, a pair of reciprocable impact members mounted in said guideways, adjustable means mounted on said frame for maintaining the tool in pivotal engagement with the rivet head during 20 its operation, and means to actuate the impact members intermittently.
6. A rivet finishing tool comprising a casing, a pair of rivet head impacting members loosely mounted therein, said members being oppositely disposed, an adjustable shaft mounted on the casing between said members for pivotally engaging a rivet head to hold the tool in position during the operation of the impact members on the rivet 25 head, and means connected to said casing and engaging the impact members to actuate the same.

In witness that I claim the foregoing I have hereunto subscribed my name this 16th day of March, 1925.

BERTRAM NEILL.
